DRIVE AND CONTROL MECHANISM FOR WASHER-EXTRACTORS

Walter Warren Egee, Yeadon, Pa., assignor to Fletcher Works Incorporated, Philadelphia, Pa., a corporation of Pennsylvania

Application November 2, 1954, Serial No. 466,297

4 Claims. (Cl. 192—3.5)

This invention relates to washer-extractors, i. e. a machine for bringing articles made of textile fabric into intimate contact with washing and/or rinsing fluids with agitation, and thereafter draining the fluid and removing substantially all the remainder of the fluid by centrifugal extraction.

It is the principal object of the present invention to provide improved driving mechanism for a washer-extractor which is rugged in construction yet simple and easy to control.

It is a further object of the present invention to provide improved mechanism for a washer-extractor in which the article containing basket can be rotated as desired for fluid extraction and in which the basket has concentrically mounted therein an agitator which can be oscillated as desired for washing.

It is a further object of the present invention to provide improved driving mechanism for a washer-extractor of the character aforesaid in which a single motor is employed.

It is a further object of the present invention to provide apparatus of the character aforesaid which is particularly suitable for large size or commercial installations.

It is a further object of the present invention to provide improved structure for rapid discharge of the washing and/or rinsing liquids.

Other objects and advantageous features of the invention will be apparent from the specification and claims.

The nature and characteristic features of the invention will be more readily understood from the following description, taken in connection with the accompanying drawings forming part thereof, in which:

Figure 1 is a fragmentary vertical central sectional view of a washer-extractor in accordance with the present invention, taken approximately on the line 1—1 of Fig. 2;

Fig. 2 is a bottom plan view of the washer-extractor shown in Fig. 1; and

Fig. 3 is a diagrammatic view of control mechanism for the agitator.

It should, of course, be understood that the description and drawings herein are illustrative merely, and that various modifications and changes may be made in the structure disclosed without departing from the spirit of the invention.

Like numerals refer to like parts throughout the several views.

Referring now more particularly to the drawings, the washer-extractor therein illustrated preferably includes a base 10 which is resiliently supported by suspension mountings (not shown) carried by fixedly mounted legs 11. The base 10 has a cylindrical housing 12 extending upwardly therefrom with an inwardly extending rim 13 at the top thereof and a hinged cover 14 carried thereby. The base 10 and housing 12, with the cover 14, provide a fluid tight receptacle or container.

2

The base 10 is preferably provided with one or more suitably controlled drain connections 15 for fluid delivery from the interior, the drain connections having either or both a pump (not shown) connected thereto to aid in liquid removal and suitable discharge connections (not shown) in accordance with the liquids to be handled.

A driving motor 17 is provided, mounted on the side of the base 10, and has a vertical shaft 18 to which the hub 19 of a pulley 20 is keyed. The pulley 20 has a peripheral groove 21, for the reception of a V-belt 22, and has extending downwardly therefrom a cylindrical clutch flange or rim 23.

Mounted on bearings 24, carried by the hub 19, the hub 25 of a main driving pulley 26 is provided. The driving pulley 26 has a plurality of peripheral grooves 27, for the reception of V-belts 28, and has a cylindrical clutch flange or rim 29 secured thereto concentric with and exteriorly disposed with respect to the rim 23. A diametrically inwardly expandable fluid pressure responsive clutch 30 is provided on the rim 29, between the rim 23 and the rim 29, and is supplied with pressure fluid through a fluid connection 31 rotatable therewith and rotatably connected to a fixedly mounted pressure supply connection 32.

The belt 22 connects the pulley 20 to a pulley 33 mounted on a stud shaft 34 carried on the lower part of the base 10. The shaft 34 is connected through a reducing gear train 35 enclosed within a housing 36 and has an output shaft 37 on which a crank plate 38 is carried. The crank plate 38 has a crank pin 39 mounted thereon and connected to a connecting rod 40, adjustable in length by threaded sections 41 engaged in a turnbuckle nut 42. The connecting rod 40 is connected at its opposite end to a pin 43 which is mounted on a crank plate 44. The crank plate 44 is journaled on a bearing 45 on the hub 46 of a clutch pulley 47. The pulley 47 is secured onto a main shaft 48 by a key 49, and the inner race of the bearing 45 is held onto the hub 46 by a washer 50 and nut 51 on the lower end of the shaft 48. The hub 46 has concentrically disposed with respect thereto a flange or rim 52 and the crank plate 44 has mounted thereon a rim 53, concentric with and outwardly disposed with respect to the rim 52. Mounted on the rim 53, and interposed between the rim 52 and the rim 53, a diametrically inwardly expandable pressure fluid responsive clutch 55 is provided, which is supplied with pressure fluid through a flexible fluid connection 56.

The shaft 48, above the hub 46, is provided with an axial thrust bearing ring 57 and a cylindrical bearing sleeve 58 on which a hollow cylindrical sleeve shaft 59 is mounted. The sleeve 59 has the hub 60 of a pulley 61 keyed thereto by a key 62, the pulley 61 being connected to the pulley 26 by the belts 28. The hub 60 is held in position on the shaft 59 by a nut 63 in engagement with a threaded lower portion 64' of the sleeve 59. The shaft 59 is carried in spaced upper and lower bearings 64 and 65 mounted thereon and within the interior of a central hollow cylindrical portion 66 forming part of the base 10.

In order to position the lower bearing 65, the shaft 59 has a shoulder 67 and inserts 68 and 69 are secured to and extend inwardly within the cylindrical portion 66. The bearing 64 is similarly positioned by a shoulder 70 on the shaft 59 and by inserts 71 and 72 secured to and extending inwardly within the cylindrical portion 66, the bearing 64 being permitted to move axially a limited distance as required. Lubricant for the bearings 64 and 65 can be supplied by a lubricant supply pipe 73 which ex-

tends to a lubricant supply passageway 74 formed in the portion 66 and in the inserts 71 and 72.

The upper end of the shaft 59 has a cylindrical bearing sleeve 75 in which the shaft 48 is journaled and an axial thrust bearing ring 76.

The shaft 59 has mounted thereon, and held by a nut 77 on a threaded portion 78 thereof, a housing portion 79 of substantially frusto conical shape with a lower outwardly extending flange 80 on which a basket 81 is mounted and held in any desired manner such as by rivets 82. The interior of the basket 81 is accessible when the cover 14 is raised for the insertion of the articles to be washed and otherwise treated. The basket 81 may be provided with rows of perforations 83 at the desired level for facilitating the discharge of liquid upon rotation thereof.

The shaft 48 has secured thereto, at the upper end thereof, such as by an end washer 83' and stud 84, the hub 85 of an agitator 86. The lower end of the hub 85 engages the thrust ring 76. The agitator 86 has a substantially frusto conical casing portion 87, outwardly disposed with respect to the housing portion 79 and is provided on the exterior thereof with a plurality of agitator vanes 88.

A brake band 90 is provided, having a brake lining 91 thereon, connected at one end to a fixed brake arm 92 carried by one of the legs 11 and connected at the other end by a bracket 93 to a piston rod 94. The piston rod 94 is connected to a piston (not shown) in a brake cylinder 95. The brake cylinder 95 is adapted to have air under pressure supplied thereto for brake application.

Mounted on the piston rod 94 and interposed between the brake cylinder 95 and the bracket 93, a compression spring 96 is provided for urging the brake band towards a released position.

The brake band 90 is preferably supported at a plurality of locations by horizontally slotted brackets 97, carried in the base 10, through which studs 98, secured to the band 90 extend. The studs 98 have springs 99 engaging the brackets 97 and nuts 100 on the studs 98 which urge the brake band 90 outwardly to retracted position when it is released.

A brake drum 101 is provided on the pulley 61 above the belt grooves for the belts 28, for engagement by the brake lining 91 of the brake band 90 when it is desired to stop the rotation of the basket 81, as hereinafter explained.

In order to control the action of the agitator 86, so as to accommodate different types of textile fabrics, it is preferred to provide a connection 110 to a source of air under pressure which is connected by pipes 111, 112 and 113 to adjustable pressure regulator valves 114, 115 and 116, these valves being set at the desired pressure delivery levels.

The valve 114 is connected through a solenoid controlled valve 117 which is normally closed, by a pipe 118, to the pipe 56. The valve 115 is connected through a solenoid controlled valve 119 which is normally closed, by a pipe 120 to the pipe 56. The valve 116 is connected through a solenoid controlled valve 121 which is normally closed, by a pipe 122. A solenoid controlled vent valve 123 is provided which is normally open and is connected to the pipe 56. The valves 117, 119 and 121 are controlled by a selector switch 124 which through power leads 125, 126 and 127, respectively permit of supplying fluid at the desired pressure level to the pipe 56. The valve 123 permits of venting the connection 56, as controlled by a switch 128, and its power lead 129.

In order to provide for rapid discharge or drainage of the liquid from the basket 81, the lower horizontal wall of the basket 81 has a plurality of valve seat members 130 mounted therein. The valve seat members 130 have central sleeve sections 131 for the reception of valve stems 132. The valve stems 132 have valve plates or plugs

133 secured on their upper ends and their lower ends have enlarged caps 134. Compression springs 135 mounted on the valve stems 132 between the lower ends of the sleeve sections 131 and the caps 134 normally urge the valve plates 133 to seated position.

5 A control ring 136 is provided having a side extension 137 pivotally mounted on the base 10 by a pivot 138 and having another opposite side extension 139 with which an adjustable limit stop 140 mounted on the base 10 engages.

An air cylinder 141 pivotally connected by a rod 142 to the control ring 136 is provided so that upon upward swinging movement of the ring 136 it engages a plurality of the caps 134 located near the extension 139, urges the valve stems 132 upwardly and moves the valve plates 133 from their seats for liquid discharge from the basket 81.

The mode of operation will now be pointed out.

20 With the desired washing or cleaning liquid supplied to the housing 12 and the interior of the basket 81, and with the articles of textile fabric to be treated in the basket 81, the agitator 86 can be oscillated while the basket 81 is substantially at rest.

25 With the motor 17 running, and turning the shaft 18, the pulley 20, keyed thereto, is also rotated. No pressure is supplied from the fluid connection 32 so that the clutch 30 is not effective at this time.

30 The belt 22 drives the pulley 33, and, through the reducing gear train 35, the shaft 37 is rotated to rotate the crank plate 38. Rotation of the crank plate 38 is effective through the connecting rod 40 for imparting an oscillatory motion to the crank plate 44. If pressure is supplied through the supply connection 56 to the clutch 55, so that the rims 53 and 52 are moved together, the oscillatory movement is imparted through the pulley 47 to the shaft 48 and thereby to the agitator 86 and the vanes 88 thereof. The contents of the basket 81 will then be agitated to bring the liquid into intimate contact with the articles therein.

35 By suitable adjustment of the valves 114, 115 and 116, to the desired pressure output, such for example as 20 p. s. i., 30 p. s. i. and 40 p. s. i., and selection of the desired pressure level by the switch 124, the agitator action may be gentle, moderate, or violent, in accordance with the fabrics to be handled, the slippage at the clutch 55 being determined by the pressure applied thereon.

40 When the desired agitation has been completed, the pressure is cut off from the supply connection 56 and the connection 56 vented by the valve 123, so that the clutch 55 disconnects the rims 53 and 52. The liquid can then be drained by actuating the air cylinder 141, and moving the ring 136 to a position to move the valve plates 133 to open position. Another liquid or liquids is supplied for rinsing, if desired, with agitation as before.

45 After the liquid has been drained from the housing 12, by actuation of the air cylinder 141 as previously indicated, pressure is supplied through the fluid connection 32 and the fluid connection 31 to the clutch 30 so that the rims 29 and 23 are moved together. The pulley 26, through the belts 33 drives the pulley 61, the brake band 90 being released prior to the supplying of pressure to the clutch 30.

50 Rotation of the pulley 61 effects rotation of the shaft 59 in the bearings 64 and 65 and the basket 81 is thus rotated at high speed for the centrifugal extraction of the liquid remaining in the articles in the basket 81. The openings 83 facilitate the discharge of the liquid from the interior of the basket 81 and the articles therein.

55 Upon the completion of the extraction of the liquid, the pressure is cut off from the clutch 30 and the brake band 91 can then be tightened against the drum 101 to bring the basket 81 to rest.

60 The articles in the basket 81 can then be removed, other articles introduced, and the working cycle repeated.

I claim:

1. In combination, a base, a motor mounted on said base and having a vertically disposed drive shaft, a first pulley secured to said motor shaft, a second pulley rotatably mounted with respect to said first pulley, a clutch for connecting said pulleys for rotation together, a first member rotatable with respect to said base, a second member movable with respect to said first member, a vertical shaft spaced from said drive shaft having the said second member mounted on the upper end thereof, a hollow shaft within which said vertical shaft is journaled to which said first member is connected for rotation therewith, said base having an upwardly extending hollow cylindrical portion within which said hollow shaft is journaled on spaced bearings, a pulley secured to said hollow shaft, belts connecting said hollow shaft pulley and said second pulley, a driving member secured to said vertical shaft, a first crank member journaled on said driving member, a clutch for connecting said first crank member and said driving member in driving relation, a second crank member connected to said first crank member and driven thereby, an intermediate shaft vertically disposed, a fourth pulley on said intermediate shaft connected to said first pulley by a driving belt, a speed reducing mechanism operated by said intermediate shaft and having an output shaft, a third crank member connected to said output shaft, and a connecting rod connecting said second and third crank members.

2. In combination, a base, a motor mounted on said base and having a vertically disposed drive shaft, a first pulley secured to said motor shaft, a second pulley rotatably mounted with respect to said first pulley, a fluid pressure operated clutch for connecting said pulleys for rotation together, a first member rotatable with respect to said base, a second member movable with respect to said first member, a vertical shaft spaced from said drive shaft having said second member mounted on the upper end thereof, a hollow shaft within which said vertical shaft is journaled and to which said first member is connected for rotation therewith, said base having an upwardly extending hollow cylindrical portion within which said hollow shaft is journaled on spaced bearings, a pulley secured to said hollow shaft, said hollow shaft pulley having a brake drum thereon, a brake band for engagement with said brake drum, belts connecting said hollow shaft pulley and said second pulley, a driving member secured to said vertical shaft, a first crank member journaled on said driving member, a clutch for connecting said first crank member and said driving member in driving relation, a second crank member connected to said first crank member and driven thereby, an intermediate shaft vertically disposed, a fourth pulley on said intermediate shaft connected to said first pulley by a driving belt, a speed reducing mechanism operated by said intermediate shaft and having an output shaft, a third crank member connected to said

output shaft, and a connecting rod connecting said second and third crank members.

3. In combination, a base, a motor mounted on said base and having a vertically disposed drive shaft, a first pulley having a hub secured to said motor shaft, a second pulley journaled on said hub, a clutch for connecting said pulleys for rotation together, a first member rotatable with respect to said base, a second member movable with respect to said first member, a vertical shaft spaced from said drive shaft having said second member mounted on the upper end thereof, a hollow shaft within which said vertical shaft is journaled and to which said first member is connected for rotation therewith, said base having an upwardly extending portion within which said hollow shaft is journaled on spaced bearings, a pulley secured to said hollow shaft, said hollow shaft pulley having a brake drum thereon, a brake band for engagement with said brake drum, belts connecting said hollow shaft pulley and said second pulley, a driving member secured to said vertical shaft, a first crank member journaled on said driving member, a clutch for connecting said first crank member and said driving member in driving relation, a second crank member connected to said first crank member and driven thereby, an intermediate shaft vertically disposed, a fourth pulley on said intermediate shaft connected to said first pulley by a driving belt, a speed reducing mechanism operated by said intermediate shaft and having an output shaft, a third crank member connected to said output shaft, and a connecting rod connecting said second and third crank members.

4. In combination, a housing, a first member rotatable with respect to said housing, a second member movable with respect to said first member, a motor, members connected to said motor for rotating said first member, members including a fluid pressure operated clutch for moving said second member, and members for controlling said clutch and thereby controlling the character of movement of said second member including a connection to a source of fluid under pressure, a plurality of adjustable valves connected to said connection and to said clutch for regulating the pressure of fluid from said connection to said source at a plurality of pressure levels, and selector means for said valves
